UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON.

Application filed March 23, 1922. Serial No. 545,925.

To all whom it may concern:

Be it known that I, FRANKLIN R. WHITE, a citizen of the United States, and a resident of Waterbury, in the county of New Haven 5 and State of Connecticut, have made and invented certain new and useful Improvements in Buttons, of which the following is a specification.

My invention relates to improvements in 10 buttons and more particularly to that type or class wherein the head of the button is adapted to flex and swivel with respect to the base and usually referred to as flexible buttons. It has heretofore been customary 15 in applying flexible buttons to garments or other material to do so by the use of a tack having a single prong which is forcibly driven through the garment material by a button attaching machine and headed 20 against an anvil and within an anchor member.

It is an object of the present invention to provide a button of this character which may be secured to a garment or cloth material 25 by the use of a staple fastener, that is, a fastener having two or more prongs, and to further simplify the construction of the head of the button so as to eliminate the use of the anchor member and to cause the 30 prongs of the staple fastener to spread and directly engage a portion of the base of the button.

A further object is to accomplish the aforementioned ends in a simple and expeditious manner and to provide a button having 35 all of the desirable characteristics of the usual type of flexible button and at the same time to be susceptible of more economic manufacture, and with the foregoing and 40 other objects in view, my invention consists in the improved button illustrated in the accompanying drawing and hereinafter described and claimed, and in such variations and modifications thereof as will be obvious 45 to those skilled in the art to which my invention relates, it being understood that changes may be made within the scope of what is claimed without departing from the spirit thereof.

50 The preferred embodiment of my invention is disclosed in the accompanying drawing, wherein:

Figure 1 is a sectional view of a button embodying the characteristic features of my

invention and showing it just prior to its attachment to the garment; 55

Figure 2 is a similar view showing the button attached;

Figure 3 is a view in section taken on the line 3—3 of Figure 2; 60

Figure 4 is a view in perspective of the spreading and upsetting die against which the prongs of the staple fastener are forced, and

Figure 5 is a detail view in section of the 65 base of the button.

Referring specifically to the several views, wherein similar reference numerals designate corresponding parts throughout, my improved button is composed of the head A, 70 base B, and staple fastener C.

The head A is preferably formed with a body portion 10 across the upper flared extremity of which extends the top plate 11 and which may be suitably inscribed or 75 decorated, according to the use to which the button is to be put. The lower extremity of the body portion is reduced so as to form the hollow hub 12 having the inturned lower edge 13. The base of the button B is provided with the bottom plate 14 which is adapted to rest directly against the garment material or cloth D and carries the hollow upstanding shank 15, the upper extremity 80 of which is turned so as to form the outstanding ledge 16. The hub 12 of the body portion of the button receives the upstanding shank 15 of the base therein, so that the inwardly turned flange 13 of the hub is held between the bottom plate 14 and the 85 outstanding ledge of the shank 16, whereby the head of the button is mounted for limited movement or flexure with respect to the base.

Located within the body portion of the button is the upsetting die 17, the same comprising the die base 18 and the die head 19, the latter being provided with a central depending portion 20 surrounded by the annular or circular groove 21. The base of the die fits between the upwardly extending 95 flange of the body portion and the top plate 11 and is held firmly in place thereby and with the die face 19 confronting the opening within the shank 15 of the button base.

With the parts as thus arranged, as the 105 prong fastener is forcibly driven through the garment material D it enters and passes up through the hollow shank 15 of the but-

ton base and contacts with the side walls of the groove 21 or the sloping sides of the central depending member 20 whereby the prongs of the staple fastener are spread outwardly and bent or upset directly upon the overturned upper ledge 16 of the button shank and thus become firmly attached to the base. The base of the button is accordingly firmly anchored to the cloth or garment material D by two spaced prongs of the staple fastener, so that it is capable of withstanding considerable stresses. The particular conformation of the die thus renders unnecessary the use of any additional anvil or anchor member, and, furthermore, causes the base to be held at two spaced points, thus providing a strong and rigid attachment for the button. Furthermore, the flexing or swiveling of the head of the button upon the base is not in any way limited by the overturned prongs of the fastener, as the head will be held firmly down upon the base in the position as illustrated in Figure 1 during the time that the staple fastener is being driven through the garment material and secured to the button base.

Having thus described and explained my invention, I claim and desire to secure by Letters Patent:

- 30 1. A button of the class described comprising a base formed with a bottom plate, a hollow upstanding shank carried by said bottom plate, said shank provided at its upper extremity with an outstanding ledge, a button head comprising a hollow hub formed with an inturned lower edge slidably engaging the shank of the base and limited in its movement with respect thereto by said

bottom plate and said outstanding ledge, the head of said button above said hub outwardly flared and including a top plate, a die located within said head resting against said top plate and comprising a die head extending down through the hollow hub and held in position thereby, said die head provided with a die face having a circular groove with a central projection, said die face adapted to receive the prongs of a staple fastener thereagainst and to spread and turn said prongs down directly upon the outstanding ledge of the shank of the button base.

2. A button of the class described comprising a base having a central upstanding hollow shank with an overturned upper edge forming an outwardly extending ledge, a button head including a body, a top plate extending across said body, a hub with an inturned lower edge, and a central opening, the said opening receiving the hollow shank of the button base therein and with the inturned lower edge limited by the overturned upper ledge of the shank of the base, a die located within said button head and provided with a die face confronting the hollow shank and adapted to receive the prongs of a staple fastener thereagainst and to spread said prongs down directly upon the upper overturned ledge of the base shank.

Signed at Waterbury, in the county of 70 New Haven and State of Connecticut, this third day of March, A. D. 1922.

FRANKLIN R. WHITE.
